UNITED STATES PATENT OFFICE.

GEORGE J. RUMENS, OF BALTIMORE, MARYLAND, ASSIGNOR TO GEORGE MILLER, OF BALTIMORE, MARYLAND.

CLUTCH-OPERATING MECHANISM.

1,244,376.

Specification of Letters Patent.

Patented Oct. 23, 1917.

Application filed August 11, 1916. Serial No. 114,480.

To all whom it may concern:

Be it known that I, GEORGE J. RUMENS, a subject of the King of Great Britain, residing at the city of Baltimore, in the State 5 of Maryland, have invented certain new and useful Improvements in Clutch-Operating Mechanism; and I do hereby declare the following to be a full, clear, and exact description of the invention, such as will enable others skilled in the art to which it 10 appertains to make and use the same.

This invention relates to release mechanism for hoists for automobile trucks, and has for an object to provide improved means for releasing the clutch or otherwise interrupting the hoisting motion of the body of the truck when the body has been elevated to the required distance or angle for dumping.

With the foregoing and other objects the invention comprises certain novel constructions, combinations and arrangements of parts as will be hereinafter more fully described and claimed.

25 In the drawings:—

Figure 1 is a view in side elevation of a conventional motor truck of the dumping type, certain parts being broken away to show the relation of the improved mechanism which forms the subject-matter of this 30 invention.

Fig. 2 is a sectional view in a vertical plane taken longitudinally of the truck, showing some of the parts.

35 Fig. 3 is a top plan view of a fraction of the chassis, showing the operating mechanism and showing line 2—2 as the plane of Fig. 2.

Fig. 4 is a view of the gearing to which 40 is connected the winding apparatus.

Fig. 5 is a view in edge elevation of the chain-winding sprocket.

Fig. 6 is a view in side elevation of a modified form wherein the connecting gear 45 is detached as distinguished from throwing out the clutch and showing the gearing out of engagement.

Fig. 7 is a view similar to Fig. 6, showing the gear in engagement.

50 Fig. 8 is a view similar to Figs. 6 and 7, showing a lock for the operating mechanism.

Fig. 9 is a view of a modified form of drum and operating mechanism.

Fig. 10 is a view of a different embodiment of the means of attaching the cable to the actuating mechanism. 55

Like characters of reference designate corresponding parts throughout the several views. 60

The improved device which forms the subject-matter of this application is adapted to be attached to a dumping truck of substantially the usual and ordinary type comprising a chassis frame 15, having a motor 16, clutch 17, drive shaft 18, all of substantially the usual and ordinary type. Mounted upon the chassis 15 is a body 19, the rear end of which is adapted to slide relative to the chassis, a slotted link 20 being provided for that purpose. The forward end of the body is raised to dumping position by means of a walking beam 21 pivoted upon the upright 22, and chain 23 connected with the walking beam at one 70 end at 24 while the opposite end of the walking beam at 25 is pivotally connected with the body 19. It is to be understood of course that there are two of such walking beams, chains, uprights, and other parts so 75 that the body is lifted symmetrically.

For the purpose of lifting the body the chain 23 after running under an idler 26 and also an idler 27 spaced therefrom runs over a sprocket 28. The sprocket 28 is 80 mounted upon a shaft 29 connected by a train of gears 30 with a shaft 31, which in turn is connected by means of a bevel gear 32 with the drive shaft 33, which is in turn intergeared at 34 with the drive 85 shaft 18. It is obvious that when the drive shaft 33 is rotated, therefore, through the medium of the train of gears 30, the shaft 29 is rotated to wind in the chain 23 and lift the body, the pivot 25 following the arc 90 as shown at Fig. 1.

The shaft 31 is preferably provided with a ratchet 35 and a pawl 36 is conveniently located to interact with said ratchet 35 to hold the body in raised position, when such 100 raised position has been assumed. Also a brake 37 is adapted to engage a brake disk 38 upon one of the shafts of the train of gears 30.

So far the mechanism as described is 105 found upon trucks already upon the market.

One of the train of gears 30, individually numbered 39, is connected with a shaft 40

which carries a differential drum 41 upon which is wound a cable 42. In the type shown at all the figures except Figs. 9 and 10 the cable 42 passes about a pulley 43 which is connected by means of a link 44, to the lever 45. It is obvious therefore that as the body is raised the differential drum will cause the shortening of the cable 42 to move the lever 45 in the direction indicated by the arrow at Fig. 7 to the dotted line position shown at Fig. 2 against the tension of the spring 46.

In the type shown at Figs. 1 and 2, a rod 47 is mounted slidably relative to the lever 45 and is provided with an adjustable stop 48, so that at the beginning of its travel from the full line position shown at Figs. 1 and 2 the lever 45 does not move the rod 47 but eventually engages the stop 48 and moves the stop and rod 47 to the dotted line position shown at Fig. 2. The rod 47 is in turn pivoted to the lever 49 which is actuated by the foot lever 50 so that the movement of the rod 47 also moves the two levers 49 and 50 to dotted line position as shown in Fig. 2 and throws out the clutch. Instead of employing the differential winding drum 41 a plain winding drum as shown at 41' at Figs. 9 and 10 may be employed and the cable wound directly thereabout, leaving a slack. As shown at Fig. 9 the cable 42 passes around the pulley 43 as in the other type, and the link 44 is connected to the lever 45, but in the type shown at Fig. 10 the cable 42 is connected directly to the lever 45, the other action being the same as heretofore described.

Instead of attaching the operating mechanism to throw out the clutch, a different type may be employed wherein a gear casing 51 accommodates the drive shaft 18 with a gear 52 mounted thereon, while a shaft 53 is mounted to slide longitudinally through the casing 51, and connected by universal joint with the shaft 33', the equivalent of the drive shaft 33 operating the train of gears 30. Upon the shaft 53 is mounted a gear 54 positioned to at times intermesh with the gear 52 as shown in Fig. 7, and at times to be slidably disengaged from such intermeshing as shown at Fig. 6. The sliding action of the gear 54 is accomplished by means of a lever 55 and connecting link 56 located adjacent the seat of the machine. To maintain the parts in operative positions a spring 57 is employed connected with a lever 58, one end of which is connected by a link 59 with the lever 55, and the other end of the lever connected with a rod 47' the equivalent of the rod 47, similarly engaging the lever 45. The position of the spring 57 is such that in moving the gear into and out of engagement the tension passes the center of the lever 58, as indicated at Figs. 6 and 7, to hold such walk-

ing beam at either limit of its position. Instead of employing such spring for such purpose, however, the rod 47' may be provided with a notch 60 and a detent 61 actuated by the spring 62 employed, such spring 62 being mounted on a rod 63 also slidably engaging the lever 45 so that in its initial position the spring 62 serves to hold the pawl 61 in engagement with the notch 60, but when the lever 45 moves upon its pivot the spring 62 releases the tension upon the pawl 61, and when the stop 64 is engaged the pawl 61 is also disengaged from the notch 60. In this type as shown at Fig. 8 a spring 65 is mounted upon the rod 47' so that as soon as the lever 45 engages the stop 64 to release the pawl 61 the spring 62 serves to instantly throw the gears out of engagement, which has the same effect as spring 57 when passing by the center of the lever 58.

It is believed that from the foregoing description of the several parts and their individual operations, the operation of the complete structure will be fully and absolutely understood without further description thereof.

What is claimed as new is:

1. The combination with a dumping truck employing a motor-drive dumping mechanism, of a drum connected with a rotating part of the driving mechanism, a cable wound about the drum, and means connected with the cable for releasing the mechanism transmitting power from the motor to the hoisting mechanism.

2. The combination with a dumping truck embodying a motor-driven hoist, of a sliding connecting member introduced into the transmission mechanism, a drum actuated by a rotating part of the hoisting mechanism, a cable wound about the drum, and means connecting the cable with the sliding connecting member of the transmission mechanism for releasing the sliding parts when a predetermined elevation has been reached.

3. The combination with a dumping truck embodying a motor-driven hoist, of sliding means for connecting the hoisting mechanism with the motor-drive, a winding drum carried by one of the rotating parts of the hoisting mechanism, a cable carried by the winding drum, a pivoted lever connected with the cable, and a rod connected with the sliding connecting mechanism and slidably relative to the lever.

4. The combination with a dumping truck embodying a motor-driven hoisting and transmission mechanism, of a sliding part interposed in the transmission mechanism, a lever pivoted to the truck, a rod connected with the sliding part and slidably connected with the lever, a winding drum carried by one of the rotating parts of the hoisting

- mechanism, and a cable connected with the lever and wound about the drum.
5. The combination with a dumping truck having a motor-driven hoist and transmission mechanism, of a sliding part interposed in the transmission mechanism, means to lock the sliding part into and out of engagement in the transmission mechanism, a rod connected with the sliding part, a lever pivoted upon the truck and having slidable connection with the rod, and means carried by the hoisting mechanism for actuating the lever when the body has moved to the limit of its dumping movement. ²⁵
- 10 6. The combination with a dumping truck embodying a motor-driven hoist and transmission mechanism, of a differential winding drum connected with a rotating part of the hoist, a cable wound about the differential drum, and means connected with the cable for disengaging the transmission mechanism at a predetermined point in the dumping movement of the body.
- 15 7. The combination with a dumping truck embodying a motor-driven hoist and transmission mechanism, of a lever pivoted upon the truck, a pulley connected with the lever, a differential winding drum connected with one of the rotating parts of the hoist, a cable wound about the differential drum and passing over the pulley, and means connecting the lever with the transmission mechanism whereby the transmission mechanism is disengaged when the lever is moved to a predetermined position. ³⁰
- 20 In testimony whereof I affix my signature in presence of two witnesses.

GEORGE J. RUMENS.
